PIPE HOLDER

Richard L. Kasper, 1123 Chalet Ave., New Carlisle, Ohio

Filed Sept. 16, 1964, Ser. No. 81,747

Term of patent 14 years

(Cl. D85—8)

FIG-1

FIG-5

FIG. 1 is a perspective view of a pipe holder, showing my new design;

FIG. 2 is a top plan view;

FIG. 3 is a front elevational view;

FIG. 4 is a side elevational view; and

FIG. 5 is a bottom plan view thereof.

I claim:

The ornamental design for a pipe holder, substantially as shown.
